FLUID-PRESSURE ENGINE

Leslie Harries, Coventry, England

Application October 12, 1944, Serial No. 558,415
In Great Britain April 16, 1943

2 Claims. (Cl. 123—44)

This invention relates to a fluid-pressure engine, and particularly to an internal-combustion engine, of the rotating-cylinder type, i. e., of the type having a stationary crankshaft of which the crank pin or other eccentric member is connected by connecting rods with pistons reciprocable in radially-extending cylinder bores, the cylinder bores rotating in unison about the crank-shaft axis.

With this type of engine trouble has previously been experienced from the fact of lubricant being discharged from the engine. It is an important object of the present invention to avoid this disadvantage in a very simple and satisfactory manner.

A further object of the invention is to fully enclose the rotating cylinder bores, whereby to prevent leakage of oil from causing difficulties, and at the same time to ensure the adequate cooling of the cylinders.

A further object of the invention is to allow of the manufacture of the rotating parts of the engine in a very simple manner.

A further object is to provide an improved two-stroke engine of this kind which will be adequately scavenged.

A still further object is to provide an improved two-stroke multi-cylinder engine which will be properly cooled and scavenged, and which will be very simple and compact.

For a better understanding of these and other objects and advantages of the invention, reference should be directed to the accompanying diagrammatic drawings of which—

Figure 1 is a part-sectional end elevation of an engine according to the invention, the view being taken mainly along the line I—I of Figure 2;

Figure 2 is, in the main, a longitudinal sectional elevation through the engine of Figure 1;

Figure 3 is an elevation of one of the rotor portions, Figure 4 being a cross-section thereof taken on the line IV—IV of Figure 3;

Figure 5 is an elevation of the other rotor portion, Figure 6 being a cross-section taken on the line VI—VI of Figure 5.

The construction shown is of an opposed-twin-cylinder engine adapted to operate on the two-stroke cycle, and with scavenging and with fuel injection, but the engine in this case is shown as being spark-ignited.

The engine includes a stationary casing 12 formed, for example, of a light alloy, and in the arrangement shown the casing is built up of a main part comprising a side wall 13 and a periph-

eral wall 14, and of a closure plate 15 providing the other side wall. The peripheral wall 14 carries externally annular cooling fins 17 which are broken away or removed as necessary to accommodate various accessories. The closure plate 15 is secured to the peripheral wall 14 of the main part in any convenient manner, as by means of screws 18.

The interior space of the casing 12 is of cylindrical shape, and coaxially disposed therein is a rotor 19 comprised of two main portions 20 and 21 (see Figures 3 and 5, respectively) which are secured to one another by means of bolts entered through the holes 22 provided for the purpose.

15 The side walls of the rotor and the peripheral wall thereof abut the corresponding walls of the casing 12. The joint between the two rotor portions 20, 21 is in a plane at right angles to the axis of the casing and substantially centrally 20 thereof.

Each rotor portion is formed, in this instance, with two semi-cylindrical bores 24, 25, those of one portion being complementary with those of the other so as to jointly form complete cylinder 25 bores when the portions have been studded together. Figure 2 shows liners 26 fitted into the built-up bores 24, 25, respectively. The bores extend from the outer periphery of the rotor to a central cylindrical space 28 therein, this space 30 being formed jointly by the two portions. Between the two semi-cylindrical bores in each rotor portion I provide recesses, as indicated at 29, 30, the recesses in one rotor portion being complementary to those of the other so as to 35 jointly form enclosed jacket spaces 29, 30 when the rotor portions are studded together.

The rotor portion 20 is recessed at its outer face to receive a lug 32, secured thereto by means of screws passed through holes 33 provided for the purpose, which is fast with a shaft 34. The latter is journalled (Figure 2) to rotate in a bearing 36 carried by a hollow hub 37 fast with the casing portion 15. The other rotor portion 21 is recessed at its outer face to receive a lug 39, secured thereto by means of screws passed through holes 40 provided therein for the purpose, which is fast with a shaft 41 journalled in a bearing 42 carried by a hollow hub 43 fast with the main casing portion 13. The shaft 41 is a hollow one internally journalled through bearings 45, 45 upon a stationary crankshaft 46 having a crank pin 47 which rests in the central space 28 of the built-up rotor. The crank pin has journalled upon it the big ends of connecting rods 49, 50 connected, respectively, through wrist

pins 51 with pistons 52, 53 which are adapted to reciprocate in the cylinder bores as the rotor rotates.

The other end of the crank shaft is locked to a stationary casing 55 which encloses various supplementary parts of the engine and which is bolted to the stationary rotor casing portion 13.

Disposed within the casing 55 is an eccentric or cam 57 fast on the hollow shaft 41 and engaged with the hardened steel end 58 of a plunger 59 which operates in a cylinder bore 60, the plunger head 58 being pressed by a spring 61 into contact with the cam 57.

The plunger 59 serves as an oil pump for the supply of oil for cooling and for lubricating purposes. The lower portion of the casing 55 forms a reservoir for lubricant which can be taken in past an inlet ball valve 63 into the pump cylinder and delivered through an outlet valve 64 to a pipe line 65 which is connected to a pipe line 66 communicating with a drilled bore 67 in the stationary crankshaft, whence lubricant can be delivered through the crank pin to the big end bearings in a well understood manner. The lubricant pump is also provided with a second outlet valve 69 through which oil can be delivered to a pipe line 70 leading to an annular chamber 71 provided partly by the shaft 34 and partly by the bearing 36, the annular chamber communicating by means of radial passages 72 with an interior chamber 73 from which the oil can pass by passages 74 (see Figures 3 and 4) to openings 75 provided in a lip 76 of the lug 32.

In this way, oil for cooling purposes is supplied to the jacket chambers 29, 30. From these chambers the oil can exhaust through holes 78 in a lip 79 of the lug 39, the holes 78 communicating by passages 80 in the lug 39 with oil-exhaust passages 81 in the metal of the hollow shaft 41, from which the oil is returned by gravity to the reservoir in the lower portion of the casing 55.

Surplus oil from the big-end bearings and rotor cylinder bores can drain back to the reservoir along the pipe 82 (Figure 2) communicating with the lower portion of the periphery of the casing 12.

Fast on the hollow shaft 41 is also a double-acting eccentric or cam 84 which engages the movable element 85 of a fuel-injection pump, diagrammatically shown at 86, and also the plunger 88 of a fuel injector 89, the latter being disposed to be actuated approximately 45° in advance of the top-dead-centre position.

Fast on the hollow shaft 41 is also a gear 92 in mesh with a pinion 93 driving the rotor shaft of a magneto 94, by which current for ignition purposes can be supplied along a lead 95 to a sparking plug 96 disposed to be at the top-dead-centre position.

The gear 92 is also in mesh with a gear 98 on a layshaft 99 by which the rotor of a blower, diagrammatically indicated at 100, can be driven. The blower delivers compressed air to a pipe line 102 (Figure 1) connected with an inlet manifold 103 which is bolted to the casing at 104, and the interior of the manifold communicates with the interior of the stationary casing 12 over an area of approximately 45°, i. e., through an inlet port bounded by the ends 105 and 106.

An exhaust manifold 108 (Figure 2), secured to the stationary casing portion 15 by bolts 109, communicates with a main, arcuate, exhaust port 110, in the side wall 15 of the stationary casing, which also extends over an angle of approximately 45° and which angularly overlaps slightly the

inlet port 105, 106. Each cylinder bore has on one side a kidney-shaped exhaust port 112 situated so as to be uncovered by the piston, during the rotation of the rotor, when the latter has travelled approximately two-thirds of its stroke from the out-centre position.

An annular sealing ring 114 is mounted in the rotor around each exhaust port 112, and an annular sealing ring 116 is mounted in the rotor round each of the outer ends of the cylinder bores.

The operation of the engine is as follows: Figure 2 shows a piston 52 at the top-dead-centre position. A charge in the outer end of the cylinder bore has been compressed and is being ignited, so that the power stroke of this piston is just beginning. The exhaust port 112 of the cylinder is positioned to open (i. e., to become aligned with the main exhaust port 110 in the stationary casing 12) when the rotor has turned approximately 125° from the top-dead-centre position and to fully close when the rotor has travelled approximately 210° from the top-dead-centre position. The air inlet port 105, 106 opens when the rotor has travelled approximately 188°, and closes at approximately 242°, from the top-dead-centre position. During this period of overlap scavenging takes place. On closure of the inlet port the new air charge in the bore becomes further compressed as the rotor rotates, and an appropriate fuel is injected by the injector approximately 45° before the firing point is reached, which again occurs after one complete revolution of the rotor.

It will be understood that the firing strokes of both pistons successively commence when they are at the out-centre position, so that there are two evenly-distributed power strokes for each rotor revolution, the two cylinders successively using the same inlet port 105, 106, the same injector 89, the same sparking plug 96, and the same exhaust port 110.

What I claim as my invention and desire to secure by Letters Patent of the United States is:

1. An internal-combustion engine comprising a casing with a substantially cylindrical interior space, a substantially cylindrical rotor mounted to revolve in said casing in contact with the walls thereof, said rotor having at least two radial cylinder bores therein extending from the periphery to a central space in said rotor, the latter also having, between said bores, enclosed jacket spaces, cylindrical liners in said bores, a stationary eccentric member disposed in said central space, pistons connected with said eccentric member so as to reciprocate within said liners, respectively, when said rotor rotates, means for supplying cooling fluid to said jacket spaces and for exhausting it therefrom, an induction opening in said casing disposed to successively co-operate with the outer ends of said bores during the rotation of said rotor, an exhaust opening in said casing disposed to successively co-operate with openings through the walls of said bores, said latter openings disposed so as to be uncovered by said pistons during the rotation of said rotor, sealing means carried by at least one face and the periphery of said rotor on opposite sides of said bores for sealing said rotor in said casing and confining the cooling medium within said jacket spaces, and ignition means carried by said casing and disposed to successively coact with the outer ends of the cylinder bores at the appropriate times.

2. An internal-combustion engine comprising

a casing with a substantially cylindrical interior space, a substantially cylindrical rotor coaxially mounted to revolve in said casing, said rotor built up of two main portions bolted to one another and jointly providing at least two radial cylinder bores extending from the periphery to a central space in said rotor, said parts also jointly providing, between said bores, enclosed jacket spaces, cylindrical liners in said bores, means for supplying cooling fluid to said jacket spaces, a stationary member disposed eccentrically in said central space, pistons within said liners, said pistons connected with said eccentric member by connecting rods so as to reciprocate within said bores, respectively, when said rotor rotates, an 15

induction pipe in said casing disposed to successively co-operate with the outer ends of said bores during the rotation of said rotor, an exhaust opening in said casing disposed to successively co-operate with openings through the walls of said bores between the ends thereof, said latter openings disposed so as to be uncovered by said pistons during the rotation of said rotor, and sealing rings in said rotor round said latter openings, said rings sealing against the adjacent side wall of the casing, and further sealing rings in said rotor round the outer ends of said bores, said further rings sealing against the cylindrical wall of the casing.

LESLIE HARRIES.
